UNITED STATES PATENT OFFICE.

GEORGE B. ALLEN, OF ATLANTA, GEORGIA.

ROTATABLE BRUSH.

1,425,435.

Specification of Letters Patent. Patented Aug. 8, 1922.

Application filed April 11, 1919. Serial No. 289,247.

To all whom it may concern:

Be it known that I, GEORGE B. ALLEN, a citizen of the United States, residing at Atlanta, in the county of Fulton and State of Georgia, have invented certain new and useful Improvements in Rotatable Brushes, of which the following is a specification.

My invention relates to improvements in rotatable brushes adapted for use in cleaning the teeth, while not necessarily restricted to this use.

An important object of the invention is to provide a device of the above-mentioned character which is of simplified construction and embodies means whereby the cleaning element may be easily removed, when desired.

Other objects and advantages of the invention will be apparent during the course of the following description.

In the accompanying drawings forming a part of this specification and in which like numerals are employed to designate like parts throughout the same:

25 Figure 1 is a side elevation of a brush embodying my invention;

Figure 2 is a central vertical longitudinal sectional view through the same, parts being shown in elevation;

30 Figure 3 is an end elevation of the device;

Figure 4 is a transverse sectional view, taken on line 4—4 of Figure 1;

Figure 5 is a similar view, taken on line 5—5 of Figure 1;

35 Figure 6 is a fragmentary perspective view of the cleaning element;

Figure 7 is a similar view of the coupling to receive one end of the body portion of the cleaning element; and

40 Figure 8 is a similar view of the second coupling to receive the other end of the body portion of the cleaning element.

In the drawings, wherein for the purpose of illustration is shown a preferred embodiment of my invention, the numeral 10 designates a tubular handle, preferably formed

45 of celluloid, although it may be formed of any suitable material. This tubular handle is provided near its forward end with a milled portion 11. At the extreme forward end of the tubular handle is a guard 12, preferably formed integral therewith. This guard is curved longitudinally and transversely, as shown.

50 55 Rotatable within the tubular handle 10 is a shaft 13, provided at its rear end with a

milled head or nut 14, preferably formed integral therewith. The longitudinal displacement of the shaft 13 is prevented by a screw 15, engaging with the tubular handle 60 10 and projecting into an annular groove 16, formed in the forward portion thereof.

The numeral 17 designates a rotatable cleaning element, embodying bristles 18, carried upon the longitudinal body portion 65 19. This longitudinal body portion is preferably formed of twisted strands of wire having the bristles 18 interwoven therein. The cleaning element 17 is circular in cross section and decreases in diameter toward its 70 opposite ends, as shown. The body portion 19 is flexible to a certain extent and the ends thereof are adapted for insertion within tubular couplings 20 and 21, such ends fitting snugly within these tubular couplings, so that the cleaning element is locked 75 to the tubular couplings for rotation therewith.

Attached to the forward end of the guard 12 is a spring element 22, as shown at 23. 80 This spring element is provided with a circular opening 24 rotatably receiving the coupling 20, while the coupling 21 has a shank 25, formed polygonal in cross section and adapted for insertion in a correspondingly shaped recess 26 formed in the forward end of the shaft 13. The couplings 20 and 21, carried by the body portion 19 may be readily inserted within the openings 24 and 26, by slightly bending or bowing the 90 body portion 19 or bending the spring 22, or bending both the spring and the body portion 19.

In the use of the device, when the parts are assembled as shown in Figure 1, the forward end of the same is placed in the mouth so that the rotatable cleaning element 17 contacts with the teeth, the guard 12 contacting with the cheeks. This guard will tend to hold the device in place in the mouth while 95 the shaft 13 may be rotated by turning the head or nut 14. This rotates the cleaning element or brush 17, thereby imparting a brushing or cleaning action to the teeth, which is more or less vertical, and which is 100 well known to be the proper way to clean the teeth.

It is to be understood that the form of my invention herewith shown and described is to be taken as the preferred example of the 110 same, and that various changes in the shape, size, and arrangement of parts may be re-

sorted to without departing from the spirit of the invention or the scope of the subjoined claim.

Having thus described my invention, I claim:

In a rotary tooth brush, the combination with a tubular handle having a rotatable shaft mounted therein, a cleaning element connected to said shaft and adapted to be 10 rotated thereby, a coupling member mounted at the outer end of said cleaning element, of a rigid guard carried by said tubular handle and arranged adjacent said cleaning element, the outer end of said guard terminating at one side of the axis of said 15

brush and short of the outer end of said coupling member, and a resilient bearing plate for said coupling member secured to said guard and narrowing toward its outer end and being curved inwardly and terminating approximately in alinement with the axis of the brush and provided with an opening to rotatably receive said coupling member.

In testimony whereof I affix my signature 25 in presence of two witnesses.

GEORGE B. ALLEN.

Witnesses:

H. C. CHAPMAN,
ED. M. REIMAN.
